BELT-HOLDING PAWLS FOR MACHINE GUNS

Carl G. Swebilius, Hamden, Conn., assignor to
The High Standard Manufacturing Company,
Hamden, Conn., a corporation of Connecticut

Application May 26, 1944, Serial No. 537,440

2 Claims.

(Cl. 89—33)

The present invention relates to improvements in machine guns and relates more particularly to improvements in belt-holding pawls for machine guns.

The belt-holding pawls of the present invention are adapted for use in connection with machine guns of the so-called "Browning" type, which type of machine gun is disclosed in detail in United States Patent No. 1,682,226 dated May 10, 1927.

In machine guns of the Browning type above referred to, it is the practice to employ a belt-holding pawl which serves to prevent the retrograde movement of the cartridge-belt and its load of cartridges, as the feed-pawl moves back to secure a fresh engagement to effect a subsequent step in the step-by-step movement of the cartridge-belt and its charge of cartridges. In efforts to speed-up the rate of .50 caliber and other large-caliber machine guns of the Browning type, to secure a greater rate of fire, great difficulty has been encountered in insuring the consistent performance of the belt-feed mechanism and associated parts. In instances especially where metal-link cartridge-belts are employed, one cartridge is apt to become canted with respect to an adjacent cartridge, with the liability that the belt-holding pawl as ordinarily constructed and arranged, will fail to properly hold the belt and thus permit a retrograde movement thereof when the belt-feed pawl retires. It is one of the objects of the present invention, therefore, to provide a superior belt-holding pawl which will function despite misalignment of succeeding cartridges in a belt, and thus insure the continued operation of the machine gun.

Another object of the present invention is to provide a superior belt-holding-pawl construction having a plurality of independently-movable pawls to insure against the retrograde movement of a cartridge-belt.

Another object of the present invention is to provide a superior multi-unit belt-holding pawl having simple, reliable and effective means for holding a plurality of pawls in proper relationship to facilitate their installation and removal from the machine-gun structure.

With the above and other objects in view, as will appear to those skilled in the art from the present disclosure, this invention includes all features in the said disclosure which are novel over the prior art and which are not claimed in any separate application.

In the accompanying drawing, in which cer-

tain modes of carrying out the present invention are shown for illustrative purposes:

Fig. 1 is a broken perspective view of the trunnion-block of a Browning-type machine gun, together with portions of the complementary side-plates, and showing a pair of belt-holding pawls constructed in accordance with the present invention, as being mounted in place;

Fig. 2 is a transverse sectional view taken on the line 2—2 of Fig. 1 but showing, in addition, the cover-plate, belt-feed slide cartridge-belt and associated features;

Fig. 3 is a broken detail sectional view taken on the line 3—3 of Fig. 1; and

Fig. 4 is a perspective view of the group comprising the two belt-holding pawls and their coupling-sleeve.

The machine-gun structure shown includes the usual trunnion-block 10, to the respective opposite sides of which are rigidly secured the forward ends of two complementary side-plates 11 and 12 which, as shown in Fig. 1, extend rearwardly beyond the rear end of the trunnion-block 10 to provide for the accommodation of features of the machine gun, such as the barrel-extension and the rear end of the barrel. The said trunnion-block 10 is formed with a central-longitudinal passage 13 designed and adapted to provide for the passage of the barrel of the machine gun in a manner well known in the art.

Rigidly secured to the outer face of the side-plate 11 above referred to, is a longitudinally-extending bracket 14 having its upper surface generally corresponding to the upper surface of the adjacent portion of the trunnion-block 10 and the adjacent cut-away portion of the side-plate 11. Secured to the outer face of the side-plate 12 is a bracket 15 generally corresponding to the bracket 14, save that it faces in an opposite direction.

About midway of its length, each of the brackets 14 and 15 is formed in its upper face with a transverse groove 16 having a front wall-portion 17 and a rear wall-portion 18. Adjacent its outer end, each of the wall-portions 17 and 18 is formed with a passage 19 arranged in axial alignment with the similar passage in the complementary wall-portion, and adapted to receive a pivot-pin 20.

Mounted in the transverse groove 16 in the bracket 15 are a pair of complementary belt-holding pawls 21 and 22 having their outer ends turning about the pivot-pin 20 in a manner as will hereinafter appear. The inner or free ends of the pawls 21 and 22 are adapted to engage with

the links 23 of a cartridge-belt in a manner as is shown particularly well in Fig. 2. In the particular instance shown, the cartridge-belt is of the so-called "link" type composed of a plurality of links normally coupled together by the cartridges 24 themselves, in a manner well understood in the art.

The pawls 21 and 22 are arranged side by side in the transverse groove 16 of the bracket 15, but are also designed and adapted to be mounted in the transverse groove 16 of the bracket 14, in the event that it is desired to have the cartridge-belt feed from the opposite side of the machine gun.

In its forward portion, the pawl 21 is formed with a passage 25 sized to receive the pivot-pin 20 with just sufficient clearance to permit the free swinging movement of the pawl 21. The passage 25 just referred to extends from the forward face of the pawl 21 to a point substantially midway the width of the said pawl, and communicates with a coaxial socket 26 in the rear portion of the pawl 21. The diameter of the socket 26 is larger than the diameter of the passage 25 and is adapted to freely receive the forward end of a coupling-sleeve 27.

The internal diameter of the aforesaid coupling-sleeve 27 corresponds to the diameter of the passage 25 before referred to. The complementary pawl 22 is formed in its forward portion with a socket 28 extending from the front edge or face thereof rearwardly to a point about halfway of the width of the pawl 22, and is sized to freely receive the rear portion of the coupling-sleeve 27. The rear portion of the pawl 22 is formed with a passage 29 of smaller diameter than the socket 28, though coaxial therewith, and sized to freely receive the pivot-pin 20 before referred to. The depth from rear to front of the socket 26 in the pawl 21 is so related to the length of the coupling-sleeve 27 as to accommodate slightly less than the forward half thereof. Similarly, the depth of the socket 28 from front to rear is also such as to accommodate slightly less than the rear half of the length of the coupling-sleeve 27. By virtue of the relationships just described, the coupling-sleeve 27 serves to hold the pawls 21 and 22 in spaced relationship in an axial direction, as is especially well shown in Fig. 3.

Adjacent its free end, each of the pawls 21 and 22 is formed in its under face with a spring-receiving pocket 30 receiving the upper end of one of two pawl-springs 31-31, one of which latter is located adjacent each of the pawls 21 and 22. The upper face of each of the transverse grooves 16-16 in the respective brackets 14 and 15 is formed with two spring-receiving pockets 32-32. The spring-receiving pockets 32-32 in the bracket 15 respectively receive the lower ends of the adjacent one of the two pawl-springs 31-31. When the pawls 21 and 22 are shifted from the right side of the machine gun to the left side thereof, the spring-receiving pockets 32-32 in the bracket 14 will, of course, then receive the lower ends of the pawl-springs 31-31.

As thus constructed and arranged, each of the pawls 21 and 22 may be independently pivoted about the pivot-pin 20 as a center, against the tension of its individual pawl-spring 31. In this manner, the pawls may act independently to insure the firm engagement of at least one of the said pawls with a given link 23 of the cartridge-belt, even though the other pawl may be held

in an inoperative position, due to misalignment of the cartridges, or for other cause.

By employing a coupling-sleeve 27 or its equivalent, the two pawls 21 and 22 may be assembled together and held in such position by the said coupling-sleeve while being installed in the given transverse groove 16 against the tension of the pawl-springs 31-31. Under these circumstances, the entry of the pivot-pin 20 into one of the pawls will automatically insure its free passage through the other pawl.

In a manner well known in the art, the cartridge-belt and the charge of cartridges 24 are fed from right to left over the belt-holding pawls 21 and 22 by means of a belt-feeding pawl 33 pivotally mounted in a belt-feeding slide 34, as is indicated in Fig. 2. The belt-feeding slide 34 and hence, also, the belt-feeding pawl 33 are reciprocated crosswise of the machine gun in any suitable manner well understood in the art, and have a stroke just sufficient to successively bring the cartridges 24 into a central position with respect to the machine-gun structure for being extracted from the belt and inserted into the firing-chamber of the machine gun, all in a manner well understood in the art.

As each successive cartridge is pulled over the free ends of the pawls 21 and 22, the said free ends will yield downwardly and as soon as the given cartridge has passed, one or more of the belt-holding pawls 21 and 22 will spring up to engage with the link 23 of the given cartridge and thus hold the entire series thereof against retrograde movement, while the belt-feeding pawl 33 is retiring, preparatory to another feeding action.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a machine-gun structure, the combination with the frame and the belt-feeding mechanism thereof: of a pair of belt-holding pawls located below the said belt-feeding means in position to engage with the under-portion of a cartridge-belt to hold the same against retrograde movement, the said pawls being arranged side by side with one in front of the other and each of the said pawls being formed with a socket in its side adjacent its complementary pawl, each of the said pawls also being formed in its portion remote from its complementary pawl with a pivot-receiving passage; a coupling-sleeve extending into the respective sockets in the two said pawls, a pivot-member extending through the respective pivot-receiving passages of the said two pawls and through the interior of the said coupling-sleeve and pivotally interconnecting the two said belt-holding pawls to the frame of the machine-gun structure with capacity for independent pivotal movement with respect thereto and with respect to each other; and spring-means individually and independently urging the respective free ends of the two said pawls in an upward direction for engagement with a cartridge-belt.

2. In a machine-gun structure, the combination with the frame and the belt-feeding mechanism thereof: of a pair of belt-holding pawls

located adjacent the said belt-feeding mechanism in position to engage with a cartridge-belt to hold the same against retrograde movement, the said pawls being arranged side by side and each thereof being formed with a socket in its side adjacent the other pawl, each of the said pawls being also formed in its portion remote from the other pawl with a pivot-receiving passage arranged coaxially with respect to the similar passage of the other pawl; a coupling-sleeve extending into the respective sockets in the two said pawls; a pivot-member extending through

5 the respective pivot-receiving passages of the said two pawls and through the interior of the said coupling-sleeve and pivotally-interconnecting the two said belt-holding pawls to the frame of the machine-gun structure with capacity for independent pivotal movement with respect thereto and with respect to each other; and spring-means 10 individually and independently urging the respective free ends of the two said pawls toward the said cartridge-belt for engagement therewith.

CARL G. SWEBILIUS.
